UNITED STATES PATENT OFFICE.

FRANK J. MCKENNA, OF NEW YORK, N. Y., ASSIGNOR TO CHEMICAL PREPARATIONS, INC., OF NEW YORK, N. Y., A CORPORATION OF NEW YORK.

HAIR-WAVING SOLUTION.

No Drawing.

Application filed March 26, 1928. Serial No. 264,961.

This invention relates to a new composition of matter in the form of a solution expressly adapted for permanent waving of human hair.

5 The invention has reference to a solution comprising four parts hydrazine hydroxide by weight and ninety-six parts of water, by weight.

Solutions of this character are applied to 10 the hair directly or to a pad, or to both, the saturated pad being wound around the hair and then heated for about eight minutes in an electric heater such as is used generally in permanent waving machines, or apparatus.

15 Hydrazine hydroxide $\text{NH}_2\text{NH}_3\text{OH}$ or the dihydroxide $\text{NH}_3\text{OH} \cdot \text{NH}_3\text{OH}$ is superior to the metal bases ordinarily employed in that it is slightly volatile when heated and penetrates to all of the hair wound on the curler, 20 thereby thoroughly softening it. It is submitted that it is superior to ammonium hydroxide because it is not so volatile and has no offensive odor.

Moreover, when ammonia solution is 25 heated, the ammonia gas is so volatile that it is entirely driven off before the hair has been completely softened, which causes a wave or curl that is not tight or lasting.

The solution embodying the hydrazine hydroxide when heated only slowly volatizes, 30 thereby insuring a complete softening of the hair, so that the resultant curl or wave is tight and lasting for a great period. Yet this substance is sufficiently volatile to thoroughly penetrate the hair even if the hair 35 is tightly wound on the curler.

The principle of the waving or curling

of hair by the use of an amino compound is in my opinion entirely new.

The use of the radical NH_2 is distinctly 40 superior to any method now or heretofore in use and is also superior to any compound composed of ammonia or any other alkaline hydroxide or salt.

I find that the most suitable of the amino 45 compounds for the purpose of permanently waving or curling hair is hydrazine hydroxide or hydrazine dihydroxide.

Having thus described my invention, what I claim as new is:—

1. As a new product of manufacture, a 50 solution for the curling or permanent waving of hair containing four parts hydrazine hydroxide $\text{NH}_2\text{NH}_3\text{OH}$ by weight and ninety-six parts water by weight.

2. As a new product of manufacture, a 55 solution for the curling or permanent waving of hair containing hydrazine hydroxide ($\text{NH}_2\text{NH}_3\text{OH}$) and water within the limits or range of eight parts by weight hydrazine hydroxide ($\text{NH}_2\text{NH}_3\text{OH}$) and ninety-two parts by weight of water and two parts by weight hydrazine hydroxide ($\text{NH}_2\text{NH}_3\text{OH}$), and ninety-eight parts by weight of water.

3. A method of waving hair consisting of 60 wetting a strand of hair with a solution consisting or composed of four parts hydrazine hydroxide ($\text{NH}_2\text{NH}_3\text{OH}$), by weight and ninety-six parts water by weight, winding the strand to form a curl and subjecting the 65 curl to an application of heat.

In testimony whereof I affix my signature.

FRANK J. MCKENNA.
